UNITED STATES PATENT OFFICE.

WARREN S. BELLOW'S, OF WORCESTER, MASSACHUSETTS.

DESIGN FOR A TOOL.

59,325.

Specification for Design.

Patented Oct. 11, 1921.

Application filed September 16, 1919. Serial No. 324,256. Term of patent 14 years.

To all whom it may concern:

Be it known that I, WARREN S. BELLOW'S, a citizen of the United States, residing in Worcester, county of Worcester, and State of Massachusetts, have invented a new, original, and ornamental Design for Tools, of which the following is a specification, reference being had to the accompanying drawing, forming a part thereof.

Figure 1 is a view in end elevation of a tool embodying my design.

Fig. 2 is a view in side elevation.

What I claim is—

The ornamental design for a tool as shown.

WARREN S. BELLOW'S.
